US00D717777S

(12) **United States Design Patent**
Hemesath et al.

(10) **Patent No.:** US D717,777 S
(45) **Date of Patent:** ** Nov. 18, 2014

(54) **CASE**

(71) Applicant: **Incipio Technologies, Inc.**, Irvine, CA (US)

(72) Inventors: **Timothy Alan Hemesath**, Huntington Beach, CA (US); **Derek Bryan Veldkamp**, Huntington Beach, CA (US)

(73) Assignee: **Incipio Technologies, Inc.**, Irvine, CA (US)

(**) Term: **14 Years**

(21) Appl. No.: **29/433,226**

(22) Filed: **Sep. 27, 2012**

(51) **LOC (10) Cl.** 14-03

(52) **U.S. Cl.**

USPC **D14/250**

(58) **Field of Classification Search**

USPC ..... D14/138 AA, 138 AD, 138 C, 138 G, D14/203.7, 230, 238.1, 240, 247, 248, 250, D14/253, 341, 345, 346, 439, 440, 447; D13/103, 107, 119; D3/218; 206/320; 220/662; 320/108; D6/306; 455/456.1, 455/575.1, 575.4, 575.8; 429/96; D9/415

(57) **CLAIM**

The ornamental design for a case, as shown and described.

DESCRIPTION

FIG. 1 is a front perspective view of a case showing our new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top end view thereof; and,

FIG. 8 is a bottom end view thereof.

The portions of the article shown broken away with wavy, parallel, broken cut-off lines indicate that any portion of the article beyond what is shown forms no part of the claimed design.

1 Claim, 6 Drawing Sheets
